CORNET MOUTHPIECE

Aaron S. Hulsaver, Brooklyn, N. Y.

Application August 20, 1940, Serial No. 353,335

5 Claims. (Cl. 84—398)

My invention relates to mouthpieces of the character of those used in musical instruments and refers more particularly to mouthpieces such as are used for cornets, trumpets, bugles, trombones, baritones, euphoniums, alto horns and the like.

Conventional mouthpieces are comprised of a rim against which the player presses his lips and a cup shaped cavity which emerges into the throat or bore of the mouthpiece, finally passing through an outwardly expanded or tapered opening into the horn passage.

The tone of such instruments are produced by the vibration of the lips of the player and in order to produce clear, pure tones, it is necessary that both lips vibrate synchronously or in unison with each other.

The effect of a horn is to reinforce vibrations which enter into it, due to the resonant properties of the body of air therein and the quantity and quality of resonance depends upon the volume of the enclosed air and upon the shape, as a horn is an air resonator.

Therefore it is self evident that the quantity and quality of a tone depends upon the shape and proportion of the cup of the mouthpiece or in other words, its construction and also the material of which it is made.

There is a direct connection between these conditions as it is well known, that the tone depends upon the velocity of the vibrations, the time on the continuance of the vibrations, the richness and volume upon the number of coexisting vibrations and the quality on the magnitude of the vibrating corpuscles.

The tones of a perfect instrument of this character should be clear and full in the upper register and mellow and rich in the lower, which effect is dependent upon the shape and function of the mouthpiece used.

The object of my invention is to provide a mouthpiece that has means for causing the lips to assume the proper shape for playing and keep them in that shape without excessive pressure which tends to paralyze the lips of the player and at the same time to give a certain freedom of movement without impairing the vibrations of the lips.

I attain these results by means of the special form of the cup of the mouthpiece hereinafter described and illustrated in the accompanying drawing, wherein like numerals refer to similar parts throughout the several views, in which:

Figure 1 is a longitudinal section of the improved mouthpiece.

Figure 2 is a partial section, illustrating a modification of the mouthpiece.

The mouthpiece is comprised of several elements, the body 1, bell shaped on the mouthpiece end, having a tapered outside portion 3, adapted to fit into the tube of the instrument, not shown, an inside tapered bore 4, entering into the throat 5, gradually expanding at 6, to a shoulder 7, which extends inwardly at 8, forming a lip opening 9.

This opening 9, is rounded at 10, and continues, preferably rounded, at 11, where it joins the wall 12, to which it is connected, to a perfectly circular portion 13, which in turn is connected to the tapered portion 3.

The particular shape of the bell, its diameter, taper and depth is dependent to a certain extent upon which instrument it is to be used with and varies in accordance therewith.

The shoulder 7, is the most vital part of the device, for the reason that when the lips are positioned over the opening 9, and the operator begins to blow, it is absolutely necessary that the lips must be in perfect seal with the surfaces 10 and 11.

This is provided for by the particular shape of the shoulder 7, which provides this required seal, whereby when air pressure is applied to the cup space or tone chamber 14, a partial vacuum is established under the shoulder 7, which draws in the lips and thus forms a perfect seal.

In Figure 2, the end 15, of the cup is ground flat and the ring 16, is attached thereto by any suitable means providing the shoulder 7, and it is obvious that the body 1, could be made of silver and the ring 16, of gold, providing the most perfect kinds of material to produce the best results.

Having thus described and illustrated the preferred embodiment of my invention, I do not wish to limit myself to the exact construction or arrangement of parts shown, as modifications may be made therein without departing from the spirit of the invention or scope of the claims.

I claim:

1. In a mouthpiece of the character described, a shank portion tapered for insertion in the mouth pipe of an instrument, a cup portion provided with a rounded rim extending from the shank portion, a flat shoulder under the inner periphery of said rounded rim formed to provide a partial vacuum means.

2. In a mouthpiece of the character described, a shank portion tapered for insertion in the

mouthpipe of an instrument, a cup portion having a rounded rim, providing an outwardly enlarging tone chamber extending from the shank portion, a flat shoulder extending inwardly under 5 said rounded rim providing the tone chamber with a partial vacuum means at its entrance.

3. In a mouthpiece of the character described, a conventional mouthpiece with a shank, bell and tone chamber provided with an angular shoulder 10 maintaining a partial vacuum under the inner periphery of the bell portion of said tone chamber.

4. In a mouthpiece of the character described, a shank formed to fit the mouth pipe of a musical instrument, a bell shaped tone chamber terminating in a ring shaped portion integral thereof

providing an angular shoulder under the ring shaped portion which connects with the said bell shaped tone chamber.

5. In a mouthpiece of the character described, a mouthpiece providing an outwardly enlarging tone chamber terminating in a flat surface under a ring shaped rim that is integral with said tone chamber, said rim having an opening of smaller diameter than the flat surface connected with the outwardly enlarging portion of the said tone 10 chamber, said flat portion formed to provide a partial vacuum under the rim of the inner periphery of said tone chamber.
